BY
George H. Kimmel
ATTORNEY.

UNITED STATES PATENT OFFICE.

ELMER B. SPIEGEL, OF TWO RIVERS, WISCONSIN.

CONCRETE MIXER.

Application filed April 6, 1929. Serial No. 353,053.

This invention relates to a concrete mixer and has for its primary object to provide, in a manner as hereinafter set forth, a concrete mixer wherein the mixing drum may be selectively positioned to deliver its charge on opposite sides of the support for the mixer and to receive its charge on the opposite side of the support from which the charge is delivered.

10 A further object of the invention is to provide, in a manner as hereinafter set forth, a concrete mixer as aforesaid, wherein the contents of the mixing drum may be selectively discharged therefrom in opposite directions without the necessity of changing the position of the support for the mixer.

With the foregoing and other objects in view, the invention consists of the novel construction, combination and arrangement of 20 parts as hereinafter more particularly described, and as illustrated in the accompanying drawings, wherein is shown an embodiment of the invention, but it is to be understood that such description and drawings are 25 to be taken as illustrative and that the invention is intended to be limited only by the scope of the claims hereunto appended.

In the accompanying drawings in which like numerals are employed to designate like 30 parts throughout the same:

Figure 1 is an elevation of a concrete mixer in accordance with this invention.

Figure 2 is a fragmentary sectional plan thereof.

35 Figure 3 is a fragmentary elevation showing the tilting mechanism.

Figure 4 is a perspective view of the reversible stop element forming a part of the tilting mechanism.

40 Figure 5 is an elevation of the stop element and actuating member therefor.

Referring to the drawings in detail, the numeral 1 indicates a mixing drum of conventional type having its bottom mounted, 45 as indicated at 2, on a yoke 3 to provide for axial movement of the drum with respect to the yoke. The ends of the yoke 3 are formed with oppositely disposed trunnions 4 and 5 for mounting on the bearings 6 of a pair of 50 supporting standards 7 and 8. The stand-

ard 7 is of substantially inverted V-shape having a pair of legs 9 and 10 which diverge in a downward direction and which are connected together by means of a suitable brace 11. The standard 8 is formed in the same 55 manner as the standard 7 and the description of the latter will also apply to the standard 8.

Encircling the drum, adjacent the bottom thereof, is a bevel gear 12 which is driven by a bevel pinion 13 to provide for the rotation 60 of the drum. The pinion 13 is mounted on a shaft 14 which extends through the trunnion 4 and to the outer end of which is fixedly secured a hand wheel 15 to provide 65 for the rotation of the shaft.

Formed on the outer end of the trunnion 5 is a reduced extension 16 of polygonal contour which terminates in a reduced cylindrical stub-shaft 17. In the present embodiment the shaft 17 is illustrated as being formed integral with the trunnion 5 and extension 7 although the shaft 17 may be a 70 separate piece if desired. Mounted on the extension 17 is a reversible stop element 18 which is formed adjacent one end with an opening 19 corresponding in contour to the extension 16. The element 18 is formed with 75 an inclined face 20 at the end thereof opposite the opening 19 and is further formed with a nose 21 which extends in continuation 80 of the inclined face 20. Adjacent the inclined face 20, the element 18 is provided with a pair of oppositely disposed flanges 22 and 23.

85 Mounted on the shaft 17 is an actuating block 24 which bears against the outer face of the element 18 and which is formed with a pair of inwardly extending lips 25 which are disposed in overlapping relation to the element 18. Mounted on the shaft 17 in contacting relation with the block 24 is a securing block 26. The contacting faces of the blocks 24 and 26 are formed with aligned 90 grooves 27 for the reception therein of a handle member 28 by means of which the blocks may be rotated to rock the yoke 3. A nut 29 is threaded on the outer end of the shaft 17 by means of which the blocks 24 and 26 are securely held in contacting relation 95 100

and the element 18 is maintained in position on the extension 16. When the handle member 28 is swung in a vertical arc, the trunnions 4 and 5 will be caused to pivot within the bearings 6.

With the stop element 18 positioned in the manner indicated in Figure 1, movement of such member in a clockwise direction will be arrested when the portion of the flange 23 adjacent the nose 21 comes in contact with the leg 9 and the drum 1 will be maintained in charging or mixing position as illustrated in full lines in Figure 1. Upon movement of the element 18 in a counter-clockwise direction, such movement will be arrested when the portion of the flange 23 opposite the nose 21 comes in contact with the leg 10 and the drum 1 will be maintained in discharge position as indicated in dotted lines and designated A.

If it is desired to discharge the contents of the drum on the opposite side of the standard, this may be accomplished by removing the blocks 24 and 26, reversing the element 18, and replacing the blocks. With the element 18 thus reversed, any movement of the element in a clock-wise direction will be arrested when the portions of the flange 22 opposite the nose 21 come in contact with the leg 9 and the drum will be maintained in position illustrated in dotted lines and designated B.

It is thought that many advantages of a concrete mixer in accordance with this invention will be readily apparent, and although the preferred embodiment is as illustrated and described, yet it is to be understood that various changes in the size, shape and arrangement of parts may be resorted to, so long as such changes fall within the scope of the invention as defined in the appended claims.

What I claim is:

1. In a concrete mixer of that type having a mixing drum tiltably mounted on a support, means for tilting the drum with respect to the support, said means including a reversible stop element for engagement with the support to selectively position the drum in oppositely disposed downward inclinations to provide for the discharge of the contents of the drum on opposite sides of the support.

2. In a concrete mixer of that type having a mixing drum tiltably mounted on a support, means for tilting the drum with respect to the support, said means including a reversible stop element for engagement with the support to selectively position the drum in oppositely disposed downward inclinations to provide for the discharge of the contents of the drum on opposite sides of the support, said stop element being operatively connected with the drum to move in unison therewith and having a pair of op-

positely extending flanges for respective engagement with the support upon the reversal of said element.

3. In a concrete mixer of that type having a mixing drum tiltably mounted on a support, means for tilting the drum with respect to the support, said means including a reversible stop element for engagement with the support to selectively position the drum in oppositely disposed downward inclinations to provide for the discharge of the contents of the drum on opposite sides of the support, said stop element being operatively connected with the drum to move in unison therewith and having a pair of oppositely extending flanges for respective engagement with the support upon the reversal of said element, said flanges being disposed at an inclination to the axis of the stop element.

4. A concrete mixer comprising, a support, a yoke having its ends provided with trunnions rotatably mounted on the support, a drum bodily carried by the yoke, a reversible stop element connected with one of said trunnions to rotate therewith, means for rotating said stop element, and a pair of oppositely extending flanges on said stop element for respective engagement with the support upon the reversal of the stop element to limit the rotating movement of the latter, said flanges being disposed at an inclination to the axis of the yoke to provide for positioning the drum at an upward inclination at one end of its path of tilting movement and at a downward inclination at the opposite end of its path of tilting movement.

5. A concrete mixer comprising, a support, a yoke having its ends provided with trunnions rotatably mounted on the support, a drum bodily carried by the yoke, a reversible stop element connected with one of said trunnions to rotate therewith, means for rotating said stop element, and a pair of oppositely extending flanges on said stop element for respective engagement with the support upon the reversal of the stop element to limit the rotating movement of the latter, said flanges being disposed at an inclination to the axis of the yoke to provide for positioning the drum at an upward inclination at one end of its path of tilting movement and at a downward inclination at the opposite end of its path of tilting movement, said means for rotating the stop element including a rotatable block positioned against the outer face of the stop element and having a pair of lips overlapping opposite edges of said element.

In testimony whereof, I affix my signature hereto.

ELMER B. SPIEGEL.
